UNITED STATES PATENT OFFICE.

WILLIAM H. WEIGHTMAN, OF BROOKLYN, NEW YORK.

DESIGN FOR A BOILER-TUBE.

SPECIFICATION forming part of Design No. 25,982, dated September 1, 1896.

Application filed June 16, 1896. Serial No. 595,799. Term of patent 14 years.

To all whom it may concern:

Be it known that I, WILLIAM H. WEIGHTMAN, a citizen of the United States, residing at Brooklyn, in the county of Kings and State of New York, have invented and produced a new and original Design for a Boiler-Tube, 5 of which the following is a specification.

Figure 1 is a plan view of my new design for a boiler-tube. Fig. 2 is a side elevation 10 of the same, looking in the direction of the arrow *x* in Fig. 1. Fig. 3 is a side elevation looking in the direction of the arrow *y*, Fig. 1.

This tube comprises an outer-curved diagonally-disposed bend A. At either end of the 15 curve A is the compound curved portion B, of the shape and formation shown. At or about the point C on either side of the tube is the peculiar conformation or design extending outwardly from the ends of the tube, 20 from thence slightly downward at the point E at the lower end of the tube, and slightly upward at the point F of the upper end of

the tube. From the points E and F the tube takes an outward compound sweep, falling slightly at the lower portion of the tube and 25 rising slightly at the upper portion of the tube, where it joins the compound curved portions B, hereinbefore referred to.

The peculiar and distinctive design of this 30 tube is better conveyed from an inspection of the plan and elevations shown by the drawings accompanying this application.

Having now described my design, what I 35 claim as new, and desire to secure by Letters Patent, is—

The design for a boiler-tube substantially as set forth.

In testimony whereof I affix my seal and name this 15th day of June, 1896.

WM. H. WEIGHTMAN. [i. s.]
